to Veeder-Root Incorporated, a corporation of
Connecticut

Application April 10, 1936, Serial No. 73,748

6 Claims. (Cl. 235—132)

My invention relates to counters.

It has among its objects to provide an improved counter of the high speed predetermining type having improved control mechanism associated therewith. A further object of my invention is to provide such a counter having improved control mechanism for operating an electric switch or other device automatically upon the completion of a predetermined number of counting operations, for maintaining the same operated during subsequent counting operations, and for reversely operating the same in response to a resetting operation of the counter resetting mechanism. A still further object of my invention is to provide such an improved control mechanism carried within the usual counter enclosing casing and cooperating with the usual counter mechanism provided therein having sufficient power for operating the device to be controlled while imposing a minimum of restraint on the counting mechanisms during counting and resetting and facilitating presetting of the predetermining members. Still another object of my invention is to provide such an improved mechanism adapted to operate a controlling device, as an electric switch, mounted on either of two different walls of the counter casing as may be desired to permit both vertical and horizontal mounting of the counter. These and other objects and advantages of my construction will, however, hereinafter more fully appear.

In the accompanying drawings I have shown for purposes of illustration one embodiment which my invention may assume in practice.

35 In these drawings,

Figure 1 is a plan view of a high speed counter of the predetermining type equipped with my improvement, the counting number wheels being shown in the zero position and parts being broken away to facilitate illustration;

Fig. 2 is a front elevation of the counter of Fig. 1 with parts of the casing broken away;

Fig. 3 is a sectional view of the counter shown in Fig. 2 looking from the left hand end, with parts of the casing broken away, showing the tripped position of the switch operating mechanism following completion of the predetermined count and prior to resetting;

Fig. 4 is a right hand end view of the counter shown in Fig. 2 with parts in section, showing the train of driving gears;

Fig. 5 is a sectional plan view taken on line 5—5 of Fig. 3 but showing the mechanism in switch open position;

55 Fig. 6 is a view similar to Fig. 3 showing the

resetting mechanism in partly reset position, in which the switch operating mechanism has just been cocked;

Fig. 7 is a similar view showing an optional vertical mounting of the counter in which the 5 switch is mounted on the bottom of the casing;

Fig. 8 is an end elevation showing a modified control mechanism;

Fig. 9 is a section taken on line 9—9 of Fig. 2;

Fig. 10 is a section taken on line 10—10 of 10 Fig. 2, and

Fig. 11 is a section taken on line 11—11 of Fig. 2.

In this illustrative construction, I have shown a high speed counter of the predetermining type 15 enclosed in a suitable casing 1 and comprising a plurality of operatively connected counting mechanisms, each having an adjustable predetermining number wheel 2 and an adjacent counting number wheel 3, while also having enclosed within said casing improved control mechanism hereinafter described.

The interconnected counting mechanisms A, B, C, D and E are of a usual construction, for example being shown in the Spaenburg Patent No. 25 2,040,026, issued May 5, 1936, and a detailed description thereof is not necessary. It will, however, be understood that the first or lowest order unit A is driven in any suitable manner and that the several counting mechanisms are connected 30 through usual transfer mechanism including milled transfer pinions 4, one of which is shown in Fig. 1, rotatably mounted on the transfer pinion shaft 5 and meshing with the two-tooth gear 6 and the twenty-tooth gear 7 of adjacent counting mechanism to provide a tens-transfer between each counting mechanism and the adjacent mechanism of next higher order, the usual notched locking disc 1a being provided adjacent each two-tooth gear 6. It will, also, be understood that the predetermining members 2 are 35 adjustable about their axis relative to their respective counting mechanisms to set up any predetermined number representing the desired number of counting operations. To this end the predetermining wheels have a series of radially arranged apertures corresponding to the numeral positions thereon, into which a pin 1b (Fig. 1) carried on the adjacent face of locking disc 1a enters in different angular positions of the predetermining wheel; spiral springs 1c located between the counting wheels and predetermining wheels and within the latter, serving to maintain the predetermining wheels releasably in adjusted 40 position on the pins 1b. Here it will be noted 45

50

55

Fig. 2 is a front elevation of the counter of Fig. 1 with parts of the casing broken away;

Fig. 3 is a sectional view of the counter shown in Fig. 2 looking from the left hand end, with parts of the casing broken away, showing the tripped position of the switch operating mechanism following completion of the predetermined count and prior to resetting;

Fig. 4 is a right hand end view of the counter shown in Fig. 2 with parts in section, showing the train of driving gears;

Fig. 5 is a sectional plan view taken on line 5—5 of Fig. 3 but showing the mechanism in switch open position;

Fig. 6 is a view similar to Fig. 3 showing the

that the counting wheels 3 are receivable within the peripheral flanges of the predetermining wheels upon axial movement of the latter to disengage the pin 7b during adjustment of the predetermining wheels to set up the predetermined count thereon. As shown, these predetermining members are also provided with the usual peripheral notches 8 which are aligned in the zero position of said members. These notches are adapted to be engaged by rollers 9, carried on a usual swinging frame 10, pivoted on a shaft 11 which is supported in the end walls of the casing.

In my improved construction, this frame is constantly biased by an improved spring 12 into a position in which the rollers engage the peripheries of the predetermining number wheels 2 ready to drop into notches 8 whenever the latter are in alignment; the spring 12, as a result of my improved control mechanism, being relatively light and connected to frame 10 adjacent its pivot so as to urge the rollers against the predetermining wheels with only sufficient force to insure that they will enter the notches when the latter are brought into alignment. It will, also, be understood that after the predetermined count has been reached and rollers 9 have entered notches 8 to operate the frame 10, the counting mechanism may be reset in a usual manner by rotating the wing nut 14 and slotted resetting shaft 15 to pick up the usual resetting pawls 15a carried by the counting mechanisms; the counting wheels being returned to zero and the predetermined number being again set up on the predetermining wheels, following a complete rotation of the shaft in the usual manner as a result of the usual ratchet 15c and pawls 15d provided in each counting mechanism between gear 7 and number wheel 3 and shown in Fig. 9.

Herein it will also be noted that the lowest order counting mechanism A, as herein shown, is driven in a continuous manner, as distinguished from a step-by-step actuation, through reducing gearing. To this end, a counter driving shaft 16 is journaled in the end walls of casing 1, parallel with the resetting shaft 15, and has a driving pinion 17 fixed thereto, as shown in Fig. 1, by an integral hub 17a abutting the inner wall of casing 1 and pinned to the shaft. A collar 17b is pinned to shaft 16 adjacent the opposite inner wall of casing 1 and with the hub 17a serves to locate shaft 16 axially in said casing. Said driving pinion meshes with a loose gear 18 journaled on the shaft 15 having a pinion 19 rotatable therewith, which, in turn, meshes with a loose gear 20 journaled on shaft 16. This gear 20 has a pinion 21 rotatable therewith which meshes with the driving gear 22 of unit A. Note also that in this construction the counting number wheel 3 of the lowest order counting mechanism A is driven by gear 22 through a special driving clutch shown in Fig. 11 consisting of spring pressed driving pawls 22a carried by the driving gear 22 and the forty tooth ratchet 22b fixed to the counting member wheel 3 of that mechanism. Here it will be noted that this fine tooth ratchet insures that the drive wheel 22 of counting mechanism A will begin to drive counting mechanism A very quickly upon rotation of the drive shaft 16 following resetting, without excessive lost motion.

I have also provided improved control mechanism wholly within the casing 1 and adapted to cooperate with the counting mechanisms above described to produce improved results. More particularly, it will be noted that, as shown in

Figs. 1 and 3, the shaft 11 of the predetermining mechanism has a bell crank 24, constituting a latch member, journaled thereon, adjacent the inner left hand wall of the casing (Fig. 1). This bell crank is journaled on shaft 11 between the adjacent arm 25 of frame 10 and a spacing collar 26, which occupies the space between the latch member and the casing wall. This collar and a similar collar 23 at the opposite end of frame 10, fix the frame and bell crank 24 against axial displacement on shaft 11. The bell crank 24 is adapted to be rotated by the frame 10 when the latter is operated at the end of the predetermined count, but is permitted a limited amount of angular movement relative to the frame for purposes hereinafter brought out. To this end, the hub of frame 10 (Figure 3) is provided with a laterally extending pin 27, which enters into a slot 28 in the bell crank 24; a spring 29 connected between the free ends of arm 25 and one arm 30 of the bell crank serving to urge the latter constantly in a counter-clockwise direction, as viewed in Fig. 3, into a position in which the pin 27 engages the left hand side wall of the slot 28. Also the bell crank 24 has a lower depending arm 30a constituting a latch for a normally stressed actuating mechanism, which is adapted to control the machine whose operations are being counted, a signal, or any other desired apparatus.

This actuating mechanism includes an actuating shaft 31 journaled in the end walls of the casing 1 (Fig. 5) having collars 32 and 33 pinned thereto at its opposite ends and abutting the inner right and left hand walls of the casing and an intermediate collar 34 likewise pinned thereto. The collar 33 has an actuating bell crank 35 fixed thereto for rotation with the shaft 31, including a lower generally horizontal arm 36, which cooperates with the latch arm 30a and an upstanding generally vertical arm 37, which cooperates with the resetting mechanism as hereinafter described. As shown most clearly in Figures 1 and 5, this tripping bell crank is located in a parallel plane closely adjacent the latch member 24 and has its lower arm 36 laterally offset at its extreme end into the plane occupied by latch member 24 in position to cooperate with the latch 30a thereof. A relatively powerful torsion spring 38 is provided on shaft 31 having one end bearing against arm 37 of bell crank 35 and the other abutting the casing to bias the shaft for rotation in a clockwise direction in which the arm 37 thereof is biased for engagement with a cam 39 fixed on the resetting shaft 15. It will be understood that in the normal position of the parts following resetting the resetting shaft 15 and cam 39 occupy the position shown in Figure 3, while the actuating bell crank 35 and bell crank 24 occupy the position shown in Figure 6, in which position the depending latch arm 30a of bell crank 30 is located above arm 36 and holds the actuating bell crank 35 and shaft 31 against the bias of spring 38. Here it will also be evident that the upstanding arm 37 of the actuating bell crank is free to move clockwise upon release of the same by the latch from its Figure 6 position to its Figure 3 position. The intermediate collar 34 has fixed thereto a generally horizontal cam member 40 which, as is most clearly shown in Figures 6 and 7, extends laterally on both sides of the shaft 31. This cam member 40 is adapted to control the cooperating contacts 41 of an enclosed electric switch which is attached to the exterior wall of the casing by suitable screws, not shown.

As shown in Figure 6, the switch is mounted on the rear wall of casing 1, a mounting plate 43 being suitably secured to the bottom wall of the casing for mounting the counter horizontally. In this position of the switch, an insulating button 44 is mounted in the switch casing and projects through an aperture in the rear wall of casing 1 into a position to be engaged and laterally operated by the end cam face 45 of cam member 40. The position of the parts shown in Figure 6 is that prior to the operation of the switch, while Figure 3 shows them in the operated position thereof, in which the button 44 has been moved laterally to the left to close the contacts 41. Here, of course, it will be understood that instead of the normally open switch herein shown, a normally closed switch could be provided if desired.

In Figure 7, the switch is shown in position on the bottom wall of casing 1 with the mounting plate 43 on the back wall of said casing for mounting the counter vertically. In this position of the switch, the button 44 projects upwardly through the bottom wall of the casing, as shown in Figure 7, in position to be engaged and depressed by the overhanging portion 46 of cam member 40 when the latter is moved with the actuating shaft 31 in a clockwise direction upon release of the actuating bell crank 35 by latch 30a. Means are also provided to determine the zero position of the resetting mechanism. To this end, the cam 39 has a flat portion 47 which cooperates with the flat face 48 of a spring pressed arm 49 journaled on the transfer pinion shaft 5. Here it will be understood that as cam 39 is rotated to reset the counter, the cooperating flat faces 47 and 48 are brought into alignment when the counting wheels are in the zero position and tend to stop the resetting shaft and consequently the counting wheels in this zero position.

In Figure 8, I have shown a modified construction in which the actuating shaft 31 is extended through the casing wall and has an arm 50 located externally of the casing 1 which may actuate the desired signal or other mechanism. It will be understood that in this modified construction, the cam member 40 is not used and may be omitted.

In the operation of the construction illustrated, it will be understood that with the counting number wheels 3 in the reset or zero position, the predetermining wheels 2 on the several counting mechanisms can be moved axially to disengage them from pins 1b and thereupon be rotated to set up the desired predetermined number. Also, as the counting mechanism A is driven by the driving gear train and transfers to the counting mechanisms B, C, D and E, the number wheels 3 will add until the predetermined number of counting operations have been performed, when the predetermined number will appear thereon, while the predetermining number wheels will subtract to zero. During this counting operation, the actuating bell crank 35 will be held in the position shown in Figure 6 by the depending latch arm 30a of bell crank 24, while the rollers 9 will ride over the external peripheries of the predetermining wheels. When, however, the predetermined number has been counted, the notches 8 in the predetermining wheels 2 will be aligned beneath the rollers 9, and as the rollers drop into the notches under the action of spring 12, the frame 10 will be rotated clockwise. Due to the engagement of pin 27 with the margin of slot 28 in bell crank 24, the latter will be rotated

with the frame from the position shown in Figure 6 to the position shown in Figure 3, thus tripping the actuating bell crank 35. The bell crank 35 under the action of its spring 38 rotates the shaft 31 and the cam member 40 in a clockwise direction as viewed in Figure 3 and actuates the button 44 of the switch either by the cam face 45 on the left hand end thereof, or by the overhanging portion 46 on the right hand end, as previously described, to close the contacts 41.

The control mechanism will remain in this tripped position until again cocked, and consequently the switch will remain operated. When, however, the resetting shaft 15 is rotated by the wing nut 14 to reset the counting mechanisms, the cam 39 acting on the upstanding arm 37 of actuating bell crank 35 will rotate the latter counter-clockwise and the depending latch arm 30a of bell crank 30 will again move into the position shown in Fig. 6 above arm 36, in which position of the latch the arm 36 is held releasably against the action of spring 38. As the resetting mechanism approaches the zero position of the counting wheels, the flat face 47 thereon comes into engagement with the cooperating flat face 48 of the spring pressed arm 49, which indicates to the operator that he has reached the zero position of the parts. It will be noted from the above described operation, that the bell crank 24 is positively tripped by the engagement of the pin 27 on frame 10 with the extremity of slot 28 in the latch member 24. When, however, resetting takes place, and the frame 10 is rotated counter-clockwise (Fig. 3) as rollers 9 are cammed out of the notches 8 in the predetermining wheels, the bell crank 24, while it is biased for counter-clockwise rotation by spring 29, is held by arm 36 until cam 39 has moved arm 36 out of the path of latch arm 30a. The lost motion permitted between frame 10 and latch member 24 by the pin and slot connection above described permits the bell crank 24 to remain in the position shown in Fig. 3 during the initial resetting operation above described, while also permitting the rollers 9 to be cammed out of the slots 8 at any time following tripping, as would be the case if the counter continued to count upon reaching the predetermined number.

The operation of the modification shown in Fig. 8 is believed to be obvious from the above, the actuating arm 50 being rotated in a clockwise direction, upon tripping of the actuating bell crank 35 by the latch arm 30a of bell crank 24, as previously explained.

As a result of my improvements, I have provided a counter of the predetermining type, capable of very high speed operation at, for example, 2500 to 3000 R. P. M.—speeds never before obtainable in a predetermining counter which heretofore have operated at speeds of 100 to 150 R. P. M. This is due in part to the continuous actuation of the lowest order counting mechanisms through a train of driving gears which imposes less strain on the transfer mechanism than intermittent operation, and in part to the improved controlling mechanism which, by reason of the latch mechanism employed, permits a very much lighter pressure of the rollers 9 against the peripheries of the predetermining wheels than has hitherto been possible. The importance of this will be evident when it is realized that in driving the counting mechanisms A, B, C, D, and E, the pressure of the rollers on the peripheries of the wheels retards the rotation thereof, and imposes a considerable load on the

transfer mechanism between counting mechanisms, especially when a transfer occurs to a higher order wheel when several or all of the counting mechanisms may be advanced simultaneously. With the present construction, the power for actuating the switch, for example, is obtained from the relatively strong spring 38, the force of which does not act upon the frame 10 as in former constructions, but instead acts 10 against the depending latch arm 30a of member 24 through which the reaction of spring 38 is transmitted to shaft 11 which acts as an abutment. Accordingly, the only force acting to urge the rollers against the peripheries of wheels 15 2 is that exerted by the relatively light spring 12 acting through a very short leverage, which has only sufficient pull to rotate the frame 10 and overcome the friction of the latch face. This improved construction, by which a light engagement 20 of the rollers on the peripheries of the predetermining wheels is made possible, also has the advantage that it permits the predetermining wheels to be adjusted with less difficulty and avoids the necessity for manually operated releasing mechanism hitherto used to swing the rollers 9 away from engagement with the peripheries of the predetermining wheels during axial movement of the latter to disengage the clutch pins 7b and permit subsequent rotation to preset 25 the predetermining wheels. It will, also, be evident that my improved control mechanism is adapted to be located wholly within the casing housing the counting mechanisms with which it cooperates without any increase in the dimensions of the casing, and that it is so arranged as to permit great freedom in the mounting of the counter and the location of the control switch.

While I have in this application specifically described two embodiments which my invention 40 may assume in practice, it will be understood that the forms of the same are shown for purposes of illustration and that my invention may be modified and embodied in other forms without departing from its spirit or the scope of the 45 appended claims.

What I claim as new and desire to secure by Letters Patent is:

1. A predetermining counter including a plurality of operatively connected counting mechanisms, predetermining mechanism operative after a predetermined count including predetermining means on said counting mechanisms and a pivoted frame having cooperating controlling members engaging said predetermining means, control means normally biased to controlling position, a latch controlling said control means normally biased into a position to engage and control said controlling means, means on said frame normally holding said latch against its bias and tripping the same upon operation of said predetermining mechanism, resetting means including a rotatable resetting shaft for returning said counting mechanisms and said predetermining mechanism to initial position following completion of the predetermined count, and means operable with said resetting means for moving said controlling means against its bias into position to be reengaged by said latch.

2. A predetermining counter including a plurality of operatively connected counting mechanisms, predetermining mechanism operative after a predetermined count including predetermining means on said counting mechanisms and a pivoted frame having cooperating controlling means engaging said predetermining means, control

means normally biased to controlling position, a latch controlling said control means and normally biased into a position to engage and control said control means, cooperating means on said frame and latch positively moving said latch against its bias to release said control means upon operation of said predetermining mechanism, resetting means including a rotatable resetting shaft for returning said counting mechanisms and said predetermining mechanism to initial position following completion of the predetermined count, and means operative in response to the rotation of said resetting shaft for moving said control means reversely into position to be engaged by said latch, said cooperating means having provision for lost motion between said frame and latch permitting reverse movement of said predetermining mechanism while permitting said latch to remain in tripped position.

3. A predetermining counter including a plurality of operatively connected counting mechanisms, each including a counting wheel and a predetermining wheel having a peripheral notch therein, cooperating predetermining mechanism including a movable frame having means engageable with the notches whenever the latter are in alignment therewith, means constantly biasing said frame for engagement with said predetermining wheels, resetting means including a rotatable resetting shaft for returning said counting mechanisms and said cooperating predetermining mechanism to their initial position following completion of the predetermined count, control means biased into a controlling position, a latch constantly biased into a position to latch said control means against operation, and latch operating means movable with said frame for tripping said latch to release said control means upon entry of said notch engaging means into said notches, cam means on said resetting shaft for moving said control means reversely during resetting into position to be engaged again by said latch, said latch operating means having an operating connection with said latch permitting reverse operation of said frame independently of a corresponding reverse movement of said latch.

4. A predetermining counter including an enclosing casing, a plurality of operatively connected counting mechanisms, predetermining mechanism operative after a predetermined count including predetermining means on said counting mechanisms and a cooperating pivoted frame having means cooperating with the predetermining means on said mechanisms, an electric switch having cooperating contacts and supportable in a plurality of positions on said casing, switch control means in said casing normally biased into position to control said contacts having means for controlling the latter in said plurality of positions, a latch member normally holding said control means against operation, and means on said frame for tripping said latch upon operation of said predetermining mechanism.

5. A predetermining counter including a plurality of operatively connected predetermining wheels each having a notch in its periphery, a swinging frame provided with rollers engaging the peripheries of said wheels and adapted to be received by said notches when the latter are in alignment, said notches being arranged to cam the rollers out of the notches during the operation of resetting said wheels, a relatively light spring urging said rollers towards said wheels, control means normally biased to controlling po-

- sition, a pivoted latch normally biased into a position to engage said control means and hold it out of controlling position, means for positively moving said controlling means against its bias 5 into position to be reengaged by said latch, and abutment means between said frame and latch normally holding said latch against its bias and actuating the same to release said control means upon engagement of said rollers in said notches, 10 said abutment means having provision for lost motion between said frame and latch and permitting said wheels to cam the rollers out of the notches and permitting said controlling means to be pivotally moved against its bias.
- 15 6. A predetermining counter including a plurality of operatively connected predetermining wheels each having a notch in its periphery, a swinging frame having rollers engaging the pe-
- ipheries of said wheels and adapted to be received by said notches when the latter are in alignment, said notches being arranged to cam the rollers out of said notches during resetting operation, a relatively light spring urging said rollers toward said wheels, a pivoted control member having latched and unlatched positions and normally biased into unlatched position, a pivoted latch pivoted coincidentally with said frame and normally biased into latching position 10 with respect to said pivoted control member, a pin and slot connection between said pivoted control member and latch and permitting limited pivotal movement therebetween, and means for positively moving said control member against 15 its bias and into latched position.

HARVEY N. BLISS.
